UNITED STATES PATENT OFFICE

1,994,261

FOUNTAIN PEN

Eugene K. Werner, New York, N. Y.

Application August 1, 1934, Serial No. 737,921

4 Claims. (Cl. 120—42)

This invention relates to new and useful improvements in fountain pens and more particularly it pertains to fountain pens of the type illustrated in my prior Patent No. 1,959,187, issued May 15, 1934.

It is the object of the present invention to improve the construction of fountain pens, particularly of the type which employ a soluble ink element capable of being dissolved in the presence 10 of water or other suitable fluid.

In all such pens with which I am familiar, the soluble ink element is relatively small in size, thus greatly limiting the capacity of the pen and rendering the replenishing of the soluble ink element more often necessary.

A feature of the present invention resides in a novel fountain pen feed bar assembly, which construction permits of the employment of a soluble ink element of larger size than can ordinarily be employed, thereby requiring the replacement of the soluble ink element at less frequent intervals than with pens of this type as generally constructed.

A further feature of the invention resides in a novel construction of fountain pen feed bar assembly which renders extremely simple, the operations attendant the renewal of the soluble ink element.

Other features of the invention relate to certain novel and improved constructions, arrangements and combinations of parts hereinafter described and particularly pointed out in the claims, the advantages of which will be readily understood and appreciated by those skilled in the art.

The invention will be clearly understood from the accompanying drawing illustrating the invention in its preferred forms and the following detailed description of the construction therein shown.

40 In the drawing:—

Figure 1 is a view in elevation, partly in section, of a fountain pen constructed in accordance with the present invention.

Figure 2 is an enlarged longitudinal sectional view on an enlarged scale of a portion of the pen barrel and the feed bar assembly, the view being taken substantially on the line 2—2 of Figure 1.

Figure 3 is a transverse sectional view, taken substantially on the line 3—3 of Figure 1.

Figure 4 is a transverse sectional view taken substantially on the line 4—4 of Figure 2.

Figure 5 is a fragmentary longitudinal sectional view on an enlarged scale, illustrating a slightly modified form of the invention,

Figure 6 is a transverse sectional view, taken substantially on the line 6—6 of Figure 5,

Figure 7 is a transverse sectional view taken substantially on the line 7—7 of Figure 5, and;

Figure 8 is a fragmentary longitudinal sectional view of the pen barrel. 5

Referring to the drawing by reference characters, 10 designates the pen barrel, which preferably has a transparent section 11, therein. The barrel 10 provides a reservoir for a suitable liquid 10 and the transparent barrel section provides an indicator by which the quantity of liquid contained in the barrel may be ascertained.

The pen may be provided with any type of barrel filling means which in the present embodiment of the invention consists of a piston head 12, movable through the barrel 10, by a piston rod 13, which extends through the rear end wall 14, of the barrel and which, when not in use, may be enclosed and protected against accidental operation by a cap 19, which has threaded engagement with the barrel 10, as at 20. A second cap 21, for enclosing the writing end of the pen when the pen is not in use, may be mounted upon the free end of the pen while the pen is being used. 15 20 25

The barrel 10, has one end open, and this open end will be hereinafter referred to as the forward end of the barrel.

The forward end of the barrel carries the feed bar assembly which will now be described. 30

The feed bar assembly consists of a sleeve 22, which is secured in any desired manner in the forward end of the barrel. This sleeve 22, is formed with an internal thread 23 and its inner end is closed by a perforated wall 24, having 35 openings 25, therein. Suitably secured within the sleeve 22, as for example by means of an external thread which has inter-engagement with the internal thread 23, of the sleeve 22, there is a sleeve 26. The sleeve 26 is of such length that when it is in place in the sleeve 22, its inner end will be closely adjacent to, but not in contact with the perforated wall 24, of the sleeve 22. The sleeve 26, forms the support or mount for the feed bar, which when it is in proper position with relation to the sleeve 26, will have its inner end closely adjacent to, but out of contact with the perforated wall 24, and preferably flush with the inner end of the sleeve 26. 40 45

In Figure 2 of the drawing, the feed bar is designated 27, and is provided with a recess 28, which extends longitudinally of the feed bar and has an open rear end 29. This recess 28, serves as a container for a soluble ink element such as an ink stick 30, which, by reason of the length 50 55

of the recess 28, may be of considerably larger dimensions than ink elements such as commonly employed in pens of this character.

This form of the invention operates in the following manner.

- The barrel 10 having been filled with water as heretofore described, the water passes through the perforated rear wall 24 into the recess 28, in the presence of the soluble ink element 30, 10 partially dissolving the same and forming a writing fluid. The writing fluid, during a writing operation passes through the passage 40, which is formed by longitudinally slitting the feed bar 27 and is fed by the feed bar to the writing point. 15 When it becomes necessary to position a new soluble ink element 30, the sleeve 26, is unscrewed from the sleeve 22 and upon its removal therefrom, the open end 29, of the recess 28, will be exposed for the insertion of a new soluble ink 20 element after which the sleeve 26, may be replaced and the pen will be ready for use.

That form of the invention illustrated in Figure 5, differs from the form described, only in the construction of the feed bar. In this form of the 25 invention, the soluble ink element is contained in a recess 41, which in some respect is similar to the construction shown in my prior patent. The recess 41, has an open side 42 the sleeve 26 serving to retain the soluble ink element in the 30 recess 41. This form of the invention operates in the same manner as heretofore described.

From the foregoing, it is apparent that the present invention provides a new and novel construction of fountain pen which is highly efficient 35 for the purpose intended and which is of a relatively simple construction.

While I have illustrated my invention in two preferred forms, it is to be understood that it is not to be limited to the construction shown 40 and that it might be embodied in other forms without departing from the spirit or scope thereof.

Having thus described the invention, what I claim as new and desire to secure by Letters 45 Patent of the United States, is:—

1. In a pen of the type described, a barrel, a sleeve secured in one end of the barrel, a per-

forated wall closing the inner end of said sleeve, a feed bar, said feed bar having a recess therein for the retention of a soluble ink element, and means for securing said feed bar in the aforementioned sleeve.

2. In a pen of the type described, a barrel forming a liquid reservoir, an internally threaded sleeve mounted in one end of the barrel, a perforated wall closing the inner end of said sleeve, a second sleeve threaded into the interior thread 10 of said first mentioned sleeve, and a feed bar carried by said second mentioned sleeve, said feed bar having a recess therein for the reception of a soluble ink element, said feed bar being so mounted in the second mentioned sleeve that 15 the perforated end wall of the first mentioned sleeve prevents displacement of a soluble ink element relative to the recess of the feed bar.

3. A fountain pen comprising a barrel, an internally threaded sleeve secured in the forward 20 end of said barrel, a perforated wall forming a closure for the inner end of said sleeve, a second sleeve having threaded engagement with said first mentioned sleeve, said second mentioned sleeve having an open inner end which when the 25 parts are assembled, occupies a position closely adjacent the perforated wall of the first mentioned sleeve, a feed bar carried by the second mentioned sleeve, said feed bar having a longitudinally extending recess terminating at the 30 rear end of the feed bar in an open end adapted to be closed by the perforated wall of the first mentioned sleeve when the several parts are in assembled position.

4. A feed bar assembly for fountain pens comprising a feed bar having a recess therein, said recess having an open rear end, a sleeve in which the feed bar is mounted, said sleeve having an open rear end which terminates substantially flush with the inner end of the feed bar, a sleeve 40 surrounding the aforementioned sleeve, and a perforated wall closing the inner end of the last mentioned sleeve, said perforated wall also forming a closure for the open inner end of the recess of the feed bar when the parts are in their assembled position.

EUGENE K. WERNER.
